Le Roy B. Clark INVENTOR
BY Victor J. Evans

ATTORNEY

WITNESS: *J. T. L. Wright*

UNITED STATES PATENT OFFICE.

LE ROY B. CLARK, OF WATERBURY, CONNECTICUT.

SMOKE SHIELD.

Application filed May 8, 1926. Serial No. 107,777.

This invention relates to a smoke shield for gas burners and the like, the general object of the invention being to provide means for covering the openings in the top 5 of the globe supporting part of the burner device so as to prevent smoke from the device from discoloring objects which may be close to the burner, such as a ceiling or draperies.

10 This invention also consists in certain other features of construction and in the combination and arrangement of the several parts, to be hereinafter fully described, illustrated in the accompanying drawings and 15 specifically pointed out in the appended claim.

In describing my invention in detail, reference will be had to the accompanying drawings wherein like characters denote like 20 or corresponding parts throughout the several views, and in which:—

Figure 1 is a fragmentary view of a globe and its supporting means, showing the invention in use, parts being in section.

25 Figure 2 is a plan view of Figure 1.

Figure 3 is a bottom plan view of the shield.

Figure 4 is an elevation showing the shield in position.

30 Figure 5 is a sectional view showing a modification.

As is well known, smoke and gases escaping through the openings 1 in the supporting member 2 of the globe 3 of a gas burner 35 and the like will often discolor the ceiling or wall or draperies and other objects near the burner, and it is the object of my invention to prevent this by placing a shield 4 over the member 2 and spaced therefrom so 40 that the smoke and gases passing through the openings 1 will be deflected downwardly, away from the object so that the smoke and gases will mingle with the air and thus be prevented from damaging the wall or ceiling or other object above the burner. This

45 shield is of saucer shape and inverted and is provided with a hole 5 through which passes the goose neck 6, a flange 7 being formed around the hole to frictionally engage the goose neck so that the shield is supported by the goose neck in spaced rela-

tion to the member 2. The shield may have its rear part omitted to form a recess 8 where the shield is used with a member 2 which has its rear part of solid construction, for in this case it is not necessary to have the shield extend over the solid part of the member. Extensions are left on the edges of the blank from which the shield is formed, and these extensions are bent downwardly to form legs 9 which engage the member 2, and these legs may be provided with recesses 10 for engaging the ribs 11 formed on the member 2.

Figure 5 shows a modification of the 65 shield which shows the legs omitted and the shield supported on the goose neck 6' by a separate collar 12 which is formed with a rib 13 and a flange 14 between which the edge of the shield 4' is held. Thus the shield 70 is fastened to the collar and the collar is supported on the goose neck.

I prefer to make the shield of substantially the same shape as the member 2 upon which it is used, though it will, of course, 75 be understood that it can be made of other shapes, the idea being to so make and arrange the shield that it will prevent smoke flowing through the openings in the member 2 from coming in contact with a ceiling, 80 wall or other object close to the burner. It will also be seen that the device can be easily and quickly placed in the goose neck by removing the globe and its supporting member and that the device is of such a simple 85 nature that it can be manufactured to sell at low cost.

It is thought from the foregoing description that the advantages and novel features of my invention will be readily apparent. 90

I desire it to be understood that I may make changes in the construction and in the combination and arrangement of the several parts, provided that such changes fall within the scope of the appended claim. 95

What I claim is:—

In combination with a burner pipe, its globe and globe supporting member, the globe supporting member having openings therethrough, radially disposed ribs on the upper surface of said supporting member, a 100 shield extending over the openings in the

supporting member to deflect the smoking gases passing through said openings, said shield having a part in its peripheral edge omitted to form a recess and shield provided with an opening centrally of the shield through which the burner pipe passes, supporting legs extending downwardly from

the edges of the shield and having recesses in their lower ends to receive the ribs on the supporting member.

10 In testimony whereof I affix my signature.

LE ROY B. CLARK.
